Patented May 14, 1918.

UNITED STATES PATENT OFFICE.

ROBERT C. MOORE, OF NEW YORK, N. Y.

PENCIL.

1,266,299.

Specification of Letters Patent. Patented May 14, 1918.

Application filed July 7, 1917. Serial No. 179,116.

To all whom it may concern:

Be it known that I, ROBERT C. MOORE, a citizen of the United States, residing in the city of New York, borough of Manhattan, 5 county of New York, and State of New York, have invented a certain new and useful Pencil, of which the following is a specification.

This invention relates to pencils of the 10 character provided at one end with a magazine adapted to contain writing paper which may be dispensed in desired lengths from time to time for the purpose of making notations, etc.

15 The present invention is an improvement on the structure of my prior application Serial No. 171,078, filed May 26, 1917, and the object of this invention is to simplify the prior structure, render the same more 20 economical to manufacture, and more readily operable. A further object of the invention is to render the feed of paper from the magazine more positive than heretofore through the maintaining of the paper within 25 the magazine in the form of a tight roll at all times, so that it cannot uncoil and clog the dispensing opening or slot, but will be properly guided through the slot by virtue of its tight winding assisted by suitable 30 guiding means not embodied in the prior construction.

Another important feature of the invention embodies means whereby paper is at all 35 times maintained in a most accessible position for projecting a portion thereof through the slot in the magazine to allow the projecting portion to be grasped by an operator and the desired length withdrawn from the magazine. This means is embodied in devices for limiting the rotation 40 of the paper roll in only that direction in which it is turned to force it through the slot, whereby retrograde rotation, which would carry its free end out of juxtaposition 45 relative to the slot, is precluded and the paper is maintained at all times in proper dispensing position.

50 Features of the invention, other than those specified, will be apparent from the following detailed description, when read in conjunction with the accompanying drawings.

In the accompanying drawings, I have 55 illustrated one practical embodiment of the invention, but the construction shown there- in is to be understood as illustrative, only,

and not as defining the limits of the invention.

Figure 1 is an elevation of a pencil embodying the present invention, the magazine for containing the paper being shown in 60 section.

Fig. 2 is a section on the line 2—2 of Fig. 1.

Fig. 3 is a perspective of the end of the pencil opposite to the writing end thereof 65 with the attachment removed.

Fig. 4 is a section through the casing on the line 4—4 of Fig. 1, and

Fig. 5 is a fragmental elevation of a portion of the paper previous to the winding 70 thereof in the form of a roll.

Referring to the drawings, A designates a pencil of any well known type which is sharpened at one end to provide a writing point a' and has, projecting from the opposite end thereof, a stem a. This stem is preferably polygonal in cross section and is adapted to fit within a roll of paper B so rolled or coiled that a passage is left through the center of the roll conforming in 80 section to the polygonal form of the stem a. When the roll or coil of paper B, formed as described, is positioned upon the stem a the rotation of the pencil A will, of course, impart similar movement to the roll B. 85

The roll of paper B is housed in a suitable cap or casing C, tubular in form and with its upper end fitted over the end of the pencil adjacent the base of the stem a as shown in Fig. 1. The casing C has a sliding fit 90 with the pencil A frictionally engaging the same with sufficient tightness to preclude the casing from inadvertent disengagement from the pencil but to allow of relative rotation between the pencil and the casing. 95

The casing C is provided with a longitudinal slot D substantially equal in length to the width of the paper roll B and at one side of the slot D is formed an inwardly extending baffle or involute portion d, as shown 100 in Fig. 2, so that when relative movement between the casing C and pencil A occurs in the direction of the arrow of Fig. 2, the free end of the paper will be engaged by a baffle d and directed through the slot D. 105

While the paper may be rolled tightly and left free to uncoil within the casing C, it is preferred to use the paper as illustrated in Fig. 5 wherein an elongated strip b is perforated or scored adjacent its longitudinal 110

edges as at b' . After the paper has been scored or perforated, as described, it is rolled up in the form of a roll, glue or other suitable adhesive being applied between the 5 scorings b' and the adjacent edges of the paper so that each successive convolution of paper is pasted to the preceding convolution adjacent the edges thereof. By this method of winding, the roll B cannot become inadvertently uncoiled since, in order to uncoil the paper, it is necessary to tear the same along the lines of the scoring, in which instance the paper actually uncoiled from the roll is only that much thereof that lies between the scorings b' , the remainder or those 10 portions of the paper exteriorly of the scorings remaining in rolled condition. Thus, when manufacturing the rolls one free end thereof is provided with notches b^2 which 15 cut away the edges of the paper exteriorly of the roll sufficiently to allow of the intermediate portion to be thrust through the slot D in the casing C when relative turning movement is imparted between the casing and the pencil, with the roll in position 20 within the casing. It is not intended in carrying out this invention that the paper be fed through the slot D in the amounts desired by relative rotation between the casing 25 and the pencil, this relative rotation serving only to project the paper a sufficient distance through the slot to allow the same to be readily grasped by the operator who is then 30 enabled to draw only paper forth, as desired. 35 After this has been accomplished the paper is torn off against the sharpened edge d' , at one side of the slot, and the operator proceeds to make such notations as he desires upon the paper thus removed from the 40 magazine.

During the operation of manually drawing the paper from the magazine or casing C, the paper is of course torn along the lines of the scorings b' leaving the edge of the 45 paper wound up, as shown in Fig. 1. At the conclusion of the tearing-off operation a short tongue of paper will be left protruding toward the slot, being maintained in alignment therewith by the baffle d , this being due to the fact that the said baffle overlies, or extends back of, the sharpened edge 50 d' , of the slot.

It is desirable that the paper remain in this position until further paper is to be 55 dispensed, and, accordingly, means is preferably provided to preclude such retrograde relative rotation between the casing and pencil as would serve to uncoil the paper upon the roll. A very convenient manner of 60 precluding this consists in forming the end of the pencil, adjacent the base of the stem a , with teeth so that said end of the pencil simulates a ratchet-wheel, as shown best at E in Figs. 1 and 3. The casing C is preferably 65 made of metal, and from that portion

thereof adjacent the ratchet-wheel E is stamped up a tongue or spring finger e adapted to coöperate with said ratchet. By this construction, relative rotation between the pencil and casing in such direction as to 70 allow of the feeding of the paper through the slot D may be readily accomplished, but counter-rotation is absolutely precluded. Accordingly, when this construction is employed, the free end of the paper, at the conclusion of the tearing operation, is left in alignment with the slot D and in such position that a very slight rotation between the parts will cause it to project through the opening and into a position wherein it may 75 be readily grasped to allow of the tearing-off of a further portion of the paper. 80

In the normal operation of the device, it is preferred that the operation of rotating the pencil relative to the casing, or vice versa, 85 for the purpose of projecting the paper through the slot, be carried out only to such degree as to project the paper sufficiently far to allow it to be grasped, after which operation further dispensing of the paper through the slot is effected by manually drawing the same therethrough. In practice, however, the required amount of paper may be dispensed through the slot by a continual turning of the casing or pencil, the baffle plate d 95 serving, during this operation, to tear the paper free along the scored lines b' .

In either manner of operating the device, the free end of the paper is left, at the termination of each successive dispensing operation, aligned and in juxtaposition with the dispensing slot of the casing, so that subsequent operations will cause the paper to be immediately projected through the slot as long as there is any paper left in the magazine. After all the paper has been dispensed, 100 the casing C may be readily slipped free from the pencil, those portions of the previous roll which remain may be readily dumped from the casing or removed from the stem a , and a new roll of paper may be positioned upon the stem. When casing C has been replaced, the new roll of paper may be dispensed in the same manner as the preceding roll. 110 115

In carrying out the invention, it is preferred that the stem a be formed of polygonal cross-section, and the aperture in the roll B shaped to conform thereto, as this formation of the parts obviates the necessity of 120 gluing the roll to the stem a . However, in practice, the aperture in stem a may be made circular, as well as the aperture in the roll, and said roll may be adhesively secured to the stem, as will be clearly understood. 125

An important advantage of the present invention over the prior art devices resides in its simplicity, economy of manufacture, and efficiency of operation, together with the increased amount of paper which may be car- 130

ried at any one time in the magazine. The invention embodies several features of novelty which, when employed collectively, produce a very superior structure. I wish it
 5 understood, however, that a pencil may be constructed embodying certain features of the invention without necessarily incorporating all, and it will thus be appreciated that the present invention is not restricted
 10 except as commensurate with the appended claims. I wish it understood, further, that the invention is not necessarily limited to use with a pencil, but may be embodied in pen or fountain pen construction without de-
 15 parting from the spirit of the invention.

Having thus fully described the invention, what I claim as new and desire to secure by Letters Patent, is:

1. A pencil provided at one end with a
 20 polygonal stem, a roll of paper adapted to receive said stem and be secured against rotation thereon by the polygonal configuration of said stem, a housing rotatably mounted on the pencil incasing the roll of
 25 paper, and a slot in the housing whereby relative rotation between the housing and the pencil causes the paper to be uncoiled from the roll and fed through the slot in the housing.

30 2. A pencil provided at one end with a polygonal stem, a roll of paper adapted to receive said stem and be secured against rotation thereon by the polygonal configuration of said stem, a housing rotatably mounted on the pencil incasing the roll of paper, a slot in the housing whereby relative rotation between the housing and the pencil causes the paper to be uncoiled from the roll and fed through the slot in the housing, and
 40 means for limiting rotation between the pencil and housing to one direction.

3. A pencil provided at one end with a polygonal stem, a roll of paper adapted to receive said stem and be secured against rotation thereon by the polygonal configuration of said stem, a housing rotatably mounted on the pencil incasing the roll of paper, a slot in the housing, and a baffle member co-operating with said slot, whereby relative
 45 rotation between the housing and the pencil causes the free end of the paper roll to engage with the baffle member which leads it through the slot of the housing.

4. A device of the class described embodying a pencil, a roll of paper mounted at one end thereof and secured against relative movement thereto, a housing incasing said roll of paper and mounted for rotation on the pencil, a slot in the housing, and a baffle
 50 member associated with the slot for directing the free end of the paper roll through said slot when relative rotation occurs between the housing and the pencil, in combi-

nation with a ratchet formed in the pencil, and a co-operating pawl mounted on the 65 housing for limiting the relative rotation between the pencil and the housing to the direction for unwinding the paper.

5. In a device of the class described a pencil, a housing rotatably mounted on one end of the pencil, a slot in the housing, a baffle-plate associated with the slot, and a roll of paper positioned within the housing and secured against relative rotation to the pencil, the paper of said roll being adhesively retained 70 along the edges of the roll but provided with scorings adjacent said edges to allow the intermediate portion of the paper to be torn from the roll, whereby relative rotation between the pencil and the housing projects 75 the free end of the intermediate portion of the paper through the slot and into a position wherein it may be grasped and drawn therethrough, and means for precluding retrograde movement of the paper. 80

6. In a device of the class described, a pencil, a housing rotatably mounted on one end of the pencil, a slot in the housing, and a roll of paper positioned within the housing and secured to the pencil against relative rotation, the paper of the roll being adhesively retained along its edges but provided with scorings adjacent said edges to allow the intermediate portion of the paper to be torn from the roll, whereby relative 90 rotation between the pencil and the housing projects the free end of the intermediate portion of the paper through the slot and into a position wherein it may be grasped and drawn therethrough. 95

7. In a device of the class described, a pencil, a housing mounted for rotation on one end of the pencil, a slot in the housing, a roll of paper positioned within the housing and secured to the pencil against relative 105 rotation, the paper of the roll being adhesively retained along its edges but provided with scorings adjacent said edges to allow the intermediate portion of the paper to be torn from the roll, whereby relative 110 rotation between the pencil and the housing projects the free end of the intermediate portion of the paper through the slot and into a position wherein it may be grasped and drawn therethrough, a ratchet formed 115 on the pencil, and a co-operating pawl mounted on the housing for precluding retrograde movement of the paper, so that, when a portion of the paper is torn away, the remaining free edge is retained in a position adjacent the slot, ready for subsequent projection therethrough. 120

In testimony whereof I have signed my name to this specification.

ROBERT C. MOORE.
